WELL TRAP FOR REFRIGERATOR CARS

William H. Keleher, Chicago, Ill., and Richard E. Powers, East Rochester, N. Y., assignors to Merchants Despatch Transportation Corporation and Northern Refrigerator Line Incorporated, both corporations of Delaware

Application November 27, 1946, Serial No. 712,590

2 Claims. (Cl. 182—8)

1

This invention relates to well traps for refrigerator cars of that type equipped with ice bunkers for refrigerating the commodities shipped by the melting of water ice in the bunkers, and in which the drippage water from each bunker falls into a receiving pan located under the bunker and is trapped by an interiorly or exteriorly arranged openable and closable trap, which trap in its closed position forms a water seal allowing the collected drip water to be discharged while preventing the entrance of outside warm air. More particularly the invention relates to improvements in a well trap of the outside type and comprising a hinged drip bucket or receptacle cooperating with a drain tube leading from the drip pan and forming therewith in its closed position a water seal of the character described.

Heretofore external drip buckets of the hinged type commonly used have employed weighted counterbalances to bring them back from open to normal or closed position, and to hold them in such position to maintain the water seal. In the open or downward position the bucket allows cleaning of the tube extending up into the car and its drip pan. Both the tube and the bucket require occasional cleaning because of the accumulation of foreign matter incidental to icing and to the undissolved salt used to secure low temperatures. The salt, which is used in percentages up to 30%, tends to form a hard concrete-like deposit if not removed periodically. Outside drip buckets cooperating with drain tubes but which are adapted to be manually closed and are held by latching devices in closed position have also been very commonly used.

The disadvantages of a counterweight closing means are its added weight and the fact that this type of bucket has a tendency to open and close under the vibrations of the car in motion, and to cause wear on the fulcrum pins, loss of the seal, and, in some cases, resulting in the wearing through of the fulcrum pins and loss of the bucket and counterweight. The latched type of outside drip bucket, through negligence, may be left in the unlatched position, in which case it hangs down, affords no water seal, and increases ice meltage and possible lading spoilage due to improper refrigeration.

Refrigerator cars are operated during both the winter and summer seasons. In the summer they require refrigeration by means of ice, and in the winter they require heater service. By heater service is meant the introduction of charcoal heaters in the bunkers to maintain the loads

above freezing or at the temperature required. This means that whenever cars are in heater service, all four drip tubes or drain tubes associated with the respective bunkers must be temporarily plugged with waddings of waste, or hair-felt insulation, or similar materials to prevent heat losses through the tubes. To plug the tubes, it is customary to completely stop them up with the above mentioned material from top to bottom. When a car again goes back into ice service, the plugging material must be removed and this is usually done from the interior of the car by rodding it out with a stick or bar. It cannot be pulled out in one piece from the bottom, as usually it is made up of several separate and distinct wads. During the changeover period between the heater and ice service, namely, in the spring and fall, there are certain commodities, especially bananas, which require transportation temperatures held within a few degrees of a required optimum. During these seasons of the year, cars may be changed en route across the country from heater to ice service and vice versa. This means considerable loss of time in plugging and unplugging tank drain tubes.

The main object of the present invention is to provide an external hinged type trap structure which overcomes these objections to prior traps of the character referred to and which embodies means for automatically and positively closing and holding the trap securely closed against car vibration so as to always maintain the seal and prevent wear and tear upon and the possible loss of trap parts.

A further object of the invention is to provide a novel construction of trap closing means for the purpose described, and adapted to permit of the use of a readily applicable packing for heater service, which is also readily removable for a quick and easy change from an icing to heater service, and vice-versa.

With these and other objects in view, which will appear in the course of the subjoined description, the invention consists of the novel features of construction, combination and arrangement of parts hereinafter more fully described and claimed, and as shown in the accompanying drawings, in which:

Fig. 1 is a vertical section through a portion of the bottom of a refrigerator car equipped with a well trap embodying the invention, the trap bucket appearing in section and in closed or sealing position.

Fig. 2 is a similar view showing the bucket depressed to open position.

Fig. 3 is a sectional view through the car bottom taken at right angles to that illustrated in Figs. 1 and 2 and looking toward the handle end of the bucket.

Fig. 4 is a view of the bucket closing device with its cylinder or casing appearing in section to disclose its internal parts.

Fig. 5 is a vertical transverse section through the bucket.

Fig. 6 is a view of parts appearing in Fig. 1 and illustrating the use of a packing for heater service.

Referring now more particularly to the drawings, 1 designates the insulated floor structure of a refrigerator car of the character described, and 2 designates the bottom of a tank or drip pan into which the drippage water from the melting ice is received and from which it discharges through a drain tube 3 projecting downward therefrom through the bottom of the car and through a bracket or seat plate 4 secured thereto.

The well trap, in the form of a drip bucket or receptacle 5, is arranged for cooperation with the projecting lower end of the tube 3 and is adapted to close upward about the same and to receive the drip water therefrom. In the illustrated example the bucket is provided at one end with hinge knuckles 6 pivotally connected by a fulcrum pin 7 with hinge knuckles 6' on the plate 4 to swing downward and upward between closed and open positions, and the bucket is provided at its opposite end with a handle 8 whereby it may be forced downwardly to open position and controlled or regulated, if desired, in its automatic movement upward to closed position. When closed, the upper marginal edge of the bucket seats against the plate 4 and the lower end of the tube 3 depends into the bucket to a point above the bottom of the bucket and below the water level line x, so that normally, and with water contained in the bucket up to the water line level, a seal is formed which prevents the entrance of warm outside air through the tube into the car. An overflow pipe 9 is provided at one side of the bucket for the escape of drip water through an orifice 9' whenever it rises above the water line level.

The means for automatically closing the trap bucket and positively holding it closed comprises a closing device 10 embodying spring means normally under compression to support and resist opening movement of the bucket and to exert sufficient force to close the door and hold it closed against car vibrations. As shown, this device 10 comprises a casing or cylinder closed by end caps 11 and 12. One end of a plunger rod 13 slidably extends into the cylinder through the cap 11 and the other end of this rod is provided with a hinge knuckle 14 pivotally connected by a fulcrum pin 15 with hinge knuckles 16 projecting from the bottom of the bucket near the pivoted end of the latter. The cap 12 is provided with a hinge knuckle 17 pivoted by a fulcrum pin 18 to hinge knuckles 19' on a bracket plate 19 fixed to the car bottom. The parts of the closing device above described are thus mounted to swing upward and downward with the bucket and the plunger rod to telescopically slide in the cylinder. On a portion of the rod located in the cylinder adjacent the head 11 is fitted an abutment head or washer 20 and arranged within the cylinder about the inner end of the rod and between the cap 12 and the head 20 is a coiled

spring 21. This spring is of sufficient strength and normally under sufficient compression to close the bucket and hold it closed against vibrations and all other disturbing forces in the running of the car, so that when the trap is sealed the seal will be preserved even under rough traveling conditions. The bucket, however, may be forced open by downward pressure on the handle 8 to allow the bucket to be drained and the bucket and drain tube to be cleaned whenever occasion requires, in which operation the spring of the telescopic-link closing device is additionally compressed for bucket closing reaction. The head 20 may be integral with the rod or formed independently of and fixed to or adjustably mounted on the rod, as desired. In the present instance, it is shown as having a plurality of openings 22 with any one of which the pin may be engaged to adjustably secure the pin and head to vary the working compression of the spring within desired limits. Other means for securing the same result may, however, be employed.

It will be evident from the foregoing description that the bucket will always be held closed to maintain the seal until it is intentionally forced open for cleaning or other purposes, and that a trap is thus provided which is free from the stated objections to counterweight-closed and manually-closed and latched traps.

As shown, the device 10 extends at an angle downwardly between the bottom of the car and the bottom of the bucket and forms a direct, swinging-link-connection therebetween in which the plunger 13 is slidable outwardly from the cylinder under the expansive force of the spring 21 to normally hold the bucket 5 closed or in sealing position with relation to the outlet 9. By this arrangement a resistance to upward swinging movement of the device 10, supplemental to that of the resistance of the spring 21, is established to positively hold the bucket in sealing position against shocks or vibrations in car travel tending to force the bucket downward and break the seal, so that the bucket will at all times be held in sealing position until it is forced downward by operation of the handle 8.

With this novel construction of trap it is not necessary to completely plug the drain tube in a changeover from an icing to a heater operation. On the contrary, since the trap is pressure closed, it is only necessary to dispose a sealing pad 24 of wadding of requisite thickness in the bucket, as shown in Fig. 6, so that the pressure of the closing device on the closed bucket will hold the pad clamped against the lower end of the drain tube in such manner that the wadding will be forced into and about the tube to make an airtight seal. This pad may be removed in a ready, quick and convenient manner by simply swinging the bucket open and withdrawing the pad in making a changeover from a heater to an icing operation again, thus avoiding the troubles and delays encountered in ordinary practice when wadding operations are necessary.

From the foregoing description, taken in connection with the drawings, the construction, mode of operation and advantages of our improved well trap will be readily understood and appreciated by those versed in the art without a further and extended description. It will, of course, be understood that the construction disclosed is exemplificative, and that changes in the form, construction and arrangement of parts, falling within the scope of the appended claims, may be made

without departing from the spirit or sacrificing any of the advantages of the invention.

Having thus described our invention, we claim:

1. In a well-trap for refrigerator cars, the combination with a refrigerator car having an ice-water drain-outlet projecting outwardly through its bottom, of a drip-bucket hinged at one side adjacent the top thereof to the bottom of the car to swing upwardly and downwardly into and out of water receiving and sealing cooperation with the outlet, a handle attached to the bucket and projecting therefrom beyond the opposite side thereof whereby the bucket may be swung downward to water-discharging position, and a bucket-closing device extending at an angle downwardly between the bottom of the car and the bottom of the bucket and forming a direct telescopic, swinging-link-connection therebetween, said device comprising a cylinder having an opening at one end and closed at its opposite end and pivoted at the latter-named end to the car bottom, a plunger 10 slidably mounted at one end in the cylinder and extending outwardly through the opening at the first-named end of the cylinder and pivoted at its opposite end to the bottom of the bucket adjacent the hinged side of the bucket, an abutment-head 15 adjustably mounted on the plunger within the cylinder, means for securing the same in a plurality of adjusted positions, and a coiled spring in the cylinder arranged to bear at one end on the closed end of the cylinder and disposed at its opposite end about the plunger and bearing on the abutment-head and exerting pressure on said cylinder end and abutment-head to normally hold the telescopic link extended and the bucket in sealing engagement with the outlet.

2. In a well-trap for refrigerator cars, the combination with a refrigerator car having an ice-water drain-outlet projecting outwardly through its bottom, of a drip-bucket hinged at one side adjacent the top thereof to the bottom of the car to swing upwardly and downwardly into and out of water receiving and sealing cooperation with the outlet, a handle attached to the bucket and projecting therefrom beyond the opposite side 20

thereof whereby the bucket may be swung downward to water-discharging position, and a bucket-closing device extending at an angle downwardly between the bottom of the car and the bottom 25 of the bucket and forming a direct telescopic, swinging-link-connection therebetween, said device comprising a cylinder having an opening at one end and closed at its opposite end and pivoted at the latter-named end to the car bottom, a plunger slidably mounted at one end in the cylinder and extending outwardly through the opening at the first-named end of the cylinder and pivoted at its opposite end to the bottom of the bucket adjacent the hinged side of the bucket, an abutment-head 30 adjustably mounted on the plunger within the cylinder, means for securing the same in a plurality of adjusted positions, and a coiled spring in the cylinder arranged to bear at one end on the closed end of the cylinder and disposed at its opposite end about the plunger and bearing on the abutment-head and exerting pressure on said cylinder end and abutment-head to normally hold the telescopic link extended and the bucket in sealing engagement with the outlet.
